United States Patent Office.

NICHOLAS S. VEDDER, OF TROY, NEW YORK.

Design No. 2,740, dated August 6, 1867.

DESIGN FOR THE DOORS OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original ornamental Design for Doors of a Cooking-Stove, of which the following is a sufficient description, reference being had to the accompanying photographs of three doors of a cooking-stove having my said design.

The design for the door N consists essentially of the shield-like compound ornament o, shaped and arranged in the horizontally-grooved panel p, so as to present the appearance represented in fig. 1; for the door Q of the ornamental strap-hinges r r and latch s, shaped and arranged on the vertically-grooved panel t, so as to appear as represented in fig. 2; and for the door U of the ornamental two-way strap hinges v v' v v' and latch v, shaped and arranged on the vertically-grooved panel x, so as to appear as represented in fig. 3.

What I claim as my invention or production, and desire to secure by Letters Patent, is—

The ornamental design for the doors N Q U of a cooking-stove, as described and shown.

NICHOLAS S. VEDDER.
